TELEVISION ANTENNA ROD FOR INDOOR USE

Marvin P. Middlemark, 96 Shore Hill Road,
Old Westbury, N.Y. 11590

Filed May 20, 1970, Ser. No. 23,064

Term of patent 14 years

Int. Cl. D14—99

U.S. Cl. D26—14

The figure in the drawing is a front elevational view of a television antenna rod for indoor use, showing my new design.

I claim:

The ornamental design for a television antenna rod for indoor use, as shown.
